DEVICE FOR MEDICAL EXAMINATION WITH
THE AID OF X-RAYS

Detlof Emanuel Berggren, Eindhoven, Netherlands, assignor, by mesne assignments, to Hartford National Bank and Trust Company, Hartford, Conn., as trustee

Application May 3, 1946, Serial No. 666,951
In the Netherlands May 13, 1942

Section 1, Public Law 690, August 8, 1946
Patent expires May 13, 1962

2 Claims. (Cl. 250—53)

1

The invention relates to a device for the medical examination with the aid of X rays, wherein the X-ray tube is movable parallel to the plane of the receiver of the rays so that it is possible to send the beam of rays in different directions through the body of the patient. The receiver of the rays may be a fluorescent screen for direct observation or indirect photography of the radiograph or a cassette with a photographic film or a plurality of such films for serial exposure. In some cases there is in front of the film a grid against secondary radiation, which grid is displaced simultaneously with the film cassette and may be brought in the correct place behind the body to be photographed.

Wherever hereinafter reference is made to a screen in the sense of a receiver of rays this term should be considered to include all the above-mentioned cases.

There is known a device of this type wherein the X-ray tube is rotatable and is coupled with the screen in such manner that upon relative displacement of the X-ray tube with respect to the screen the central ray always strikes upon the screen at the same point.

With the known device this condition is fulfilled both in the case of vertical displacement (the device is only suitable for the examination of standing or sitting patients) and of horizontal displacement of the X-ray tube.

The invention is based on the idea that with lateral displacement of the X-ray tube it is rather the object to choose a determined portion of the patient's body than to obtain an obliquely incident beam. For the latter purpose it is sufficient when the axis of the beam of rays can swing in a vertical plane. It is desirable, it is true, that the tubes should also be movable in lateral direction, but without the beam swinging round. Besides, at the same time the screen must be laterally displaced, and this in the same sense as the tube.

According to the invention, in a device for the medical examination with the aid of X rays wherein the X-ray tube is movable parallel to the plane of the screen, the X-ray tube and the screen are movable, in addition, simultaneously and in the same sense parallel to and in the transverse direction of a table board or supporting wall for the patient whilst for carrying out this movement there is provided a device with the aid of which the tube and the screen are coupled with one another in such manner that upon relative displacement of the X-ray tube with respect to the screen in the longitudinal direction of the table board or the supporting wall the central

ray always strikes upon the screen at the same point.

In the device according to the invention, the tube and the screen may be secured, as in the above-mentioned known device, to several stands adapted to roll on the floor of the room. If the device comprises a table for supporting the patient which is rotatable about a horizontal shaft, it is more efficient if, as has been proposed elsewhere, the devices for supporting the X-ray tube and the screen are secured to the table itself and follow the rotary movement of the table about its shaft.

If desired, a rod acting as a coupling element between the X-ray tube and the screen may be telescopic so that the ends need not be displaced with respect to the holder of the X-ray tube or the screen when the distance between the X-ray tube and the screen changes.

In one suitable embodiment of the device according to the invention the coupling rod is rotatable about its axis whilst there are provided means of converting the rotation of this rod about its axis into a translation of the X-ray tube or of the latter and the screen. To the rod may be secured a handle which permits it to rotate. In this case the movement has to be transferred from the rod to the screen and to the X-ray tube. It is also possible to construct the screen itself in such manner that it can be handled and be displaced in lateral direction, in which event the movement has to be transferred from the movable screen portion to the coupling rod and from the latter again to the X-ray tube.

To the X-ray tube or the screen or to both of them may be secured a toothed rack which engages a gear wheel mounted on the rod and which, upon rotation of the rod about its axis, is displaced in its longitudinal direction.

With the screen this is less simple than with the X-ray tube since the rod must be able to rotate about a horizontal axis located in the plane of the screen. In order to achieve this, the rack may be connected to the rod in such manner that it follows the movement of the rod about an axis in the plane of the screen and it may have a connection with the screen which can be displaced in accordance with this movement so that upon rotation of the rod about its own axis the rack displaces the screen in the transverse direction of the supporting table or of the supporting wall, and this in the same sense as the X-ray tube.

Different solutions are possible with a rack rigidly secured to the screen. Thus, for example, the movement of the rotating coupling rod may

2

3

be transferred to the rack by two gear wheels which are connected to one another by a flexible shaft and of which the one is coupled with the rack secured to the screen and the other with the coupling rod rotating about its axis. Another solution is that the coupling rod is connected to the screen by means of a universal joint whose centre is located in the plane of the screen. In this case a handle may be secured to the universal joint, but the device may also be constructed in such manner that the movement is transferred from the screen via the universal joint to the coupling rod.

The connection between the rod and the screen may also be obtained by a combination of a crank and a driving rod. Unless between the handle and the coupling rod a universal joint is utilized, the plane of the crank and the driving rod must pass through the axis about which the coupling rod swings with respect to the screen whilst the cross head must be secured to the screen so as to be rotatable about this axis.

The invention will be explained more fully with reference to the accompanying drawing which represents diagrammatically, by way of example, in two projections one embodiment of the invention wherein the tube and the screen are supported by a table which is rotatable about a horizontal axis, the table board taking up a vertical position.

Fig. 1 is an elevation perpendicular to the table board and

Fig. 2 is a lateral elevation.

Fig. 3 is a portion of Fig. 2 with the omission of parts located in front of it.

Fig. 4 represents part of the device in a slightly different construction.

The supporting table consists of a frame 1, a base 2 and a table board 3. The frame 1 is rotatable in the base 2 about a horizontal axis 4. The rotation occurs electrically by means of a motor and a toothed segment enclosed in a casing 5; it may also take place by hand with the aid of a crank. Besides the table board 3 columns 6 and 7 are secured in the frame 1. On each column slides a carriage. One of the carriages (8) carries an X-ray tube 9 and the other (10) carries a screen 11. When the frame takes up a vertical position the movement of these carriages is facilitated by means of counterweights (not shown). These counterweights are movable in the hollow columns 6 and 7 and may be connected to the carriages with the aid of chains or steel ropes which run on pulleys. A slide 12 is movable in the carrier 8 in a direction perpendicular to the plane of the frame 1. This slide may also be connected with a counterweight in order to facilitate the movement when the table occupies a horizontal or inclined position. The X-ray tube is secured to the slide 12 so as to be rotatable about an axis 13. The screen 11 is secured to two rods 14 and 15 which are adapted to slide in bushes 16 and 17 of the carriage 10 so that it is possible to modify the distance between the plane of projection and the table board. The carriages 8 and 10, the slide 12 and the rod 14 may be secured against displacement with the aid of clamping screws 18.

The X-ray tube 9 is clamped in a holder 19 which terminates in a spindle 20 which is rotatable in the supporting arm 21 of the slide 12 and which comprises a side piece 22. The axis 13 of the spindle 20 passes through the focal spot of the X-ray tube. In the side piece 22 terminates a telescopic rod 23 which consists of three

4

portions and which is rotatable about its own axis. To the thickest portion 24 are secured pins 25 whose axis is located in the plane of the screen 11 and passes through the centre thereof. These pins are rotatable in an annular stirrup 26 formed by the frame 27 in which the screen is provided.

Since the axis of the rod 23, which axis intersects the axis 13 at right angles, and the central ray of the X-ray tube are located in one plane 10 and since the axis of rotation of the pins 25 is parallel to the axis of rotation 13 and passes through the centre of the screen 11, the central ray strikes upon the centre. If the carriage 10 with the screen is raised out of the position shown 15 along the column 7 whereas the carriage 8 is held fast, the distance between the focal spot and the centre of the screen decreases and the inclination of the rod 23 is modified. The portions of the rod 23 slide into one another and the rod rotates 20 in the stirrup 26. The spindle 20 and consequently also the central ray follow the rotary movement of the rod 23. Independently of the place taken up by the carriage 10 on the column 7, the central ray continues to pass through the 25 centre of the screen.

Conversely, the carriage 10 may be set tightly and the carriage 8 may be displaced along the column 6. In this case, too, the condition that the central ray should pass through the centre 30 of the screen 11 is always fulfilled. It is consequently possible to submit any portion of the trunk of a patient standing upon a foot board 28 or, in the case of a horizontal or inclined position of the supporting table, lying on the 35 table board 3 to fluoroscopic examination at any desired angle, the shadow image will always be located approximately in the centre of the screen 11.

The X-ray tube 9 can be displaced not only 40 along the column 6 and in a direction perpendicular to the table board but also horizontally in the transverse direction of the table board. To that end the spindle 20 is not only rotatable but also slidable in the supporting arm 21. 45 Moreover, the screen 11 is movable not only along the column 7 and in a direction perpendicular to the table board but also horizontally in the transverse direction of the table board. To that end the ray-receiver proper is constructed as a 50 slide located in the frame 27.

The transverse movement of the X-ray tube 9 and the screen 11 may be brought about with the aid of the rod 23, that is to say by rotating the latter about its axis. At its end the rod 23 55 carries a gear wheel 29 which engages a toothed rack 30 which is attached to the spindle 20 which is horizontally slidable in the arm 21. The side-piece 22 is not rigidly secured to the spindle 20 but to a bush which is slidable along the spindle 60 but is not rotatable with respect to the latter, the said bush being enclosed in a fork formed by the supporting arm 21.

When the rod 23 is rotated about its axis, 65 the gear wheel 29 rotates and the X-ray tube is displaced in the lateral direction, the spindle 20 sliding through the supporting arm 21 and the bush of the side-piece 22. At that end of the rod 23 which passes through the stirrup 26 is 70 provided a handle 31 so that the rod 23 can be utilized as a handle for bringing about the movements of the carriages 8 and 10 along the columns. This handle serves at the same time to rotate the rod 23.

75 The pins 25 are not secured directly to the

portion 24 of the rod 23, but they are secured to a bush 32 in which the rod is rotatable. The portion 24 carries a gear wheel 33 whose diameter is equal to that of the gear wheel 29. It engages a toothed rack 34 which cannot be immovably secured to the screen 11 since otherwise it would leave the gear wheel as soon as the carriage 10 is raised or would prevent this carriage from being lowered. For this reason the rack 34 is mounted so as to be slidable in a bush 35 which is secured to any of the pins 25 or to the bush 32 itself (see Figs. 1 and 3). Upon rotation of the rod 23 about the pins 25 the rack 34 follows this rotary motion and remains in engagement with the gear wheel 33.

The one end of the rack 34 has a connection with the screen 11 which can be displaced in accordance with the movement around the pins 25 so that upon rotation about the horizontal axis the toothed rack runs clear of the screen but upon displacement in its longitudinal direction also sets the screen in motion. To that end the end of the rack passes through a circular slot 36 in a vertical plate 37 which is secured to the screen 11. In order to prevent the rack from sliding through the slot the end is made thinner and the slot is accordingly narrower; in order to prevent it from being drawn out of the slot it is provided on the other side of the plate with a boss 38.

Instead of a slotted plate it would also be possible to utilize a crank secured to the screen 11 and adapted to rotate about an axis which coincides with that of the pins 25, said crank gripping around the rack. It is also possible to provide two gear wheels which are connected to one another by means of a flexible shaft and of which the one is coupled with the toothed rack of the screen and the other is coupled with the gear wheel 33. In the latter case the rack may be rigidly connected to the screen 11.

Fig. 4 shows the manner in which the coupling rod 23 may be connected to the screen 11 by means of a combination of a crank and a driving rod. A crank 39 which is secured to the portion 24 passes to the outside through a slot 40 in the bush 32 and is connected with a driving rod 41. The plane of the driving rod 41 and the crank 39 passes through the axis 42 of the pins 25. A cross head 43 is secured to the screen 11 so as to be rotatable about this axis. When the rod 23 swings around the pins 25, the plane of the crank and the driving rod follows this swinging motion. The cross-head rotates in this case with respect to the screen about the axis 42 so that the movement of the rod 23 is not hampered. When the handle 31 is turned, the crank 39 swings through the slot 40 and the driving rod 41 pushes or pulls the screen 11 in the direction of the axis 42.

If the conversion of the rotary motion of the rod 23 about its axis into a rectilinear motion is effected, in the case of the X-ray tube, with the aid of a gear wheel and a toothed rack and, in the case of the screen, with the aid of a crank and a driving rod, the movement of the X-ray tube is only approximately similar to that of the screen, but in the case of a crank which is not excessively short the approximation within the stroke of the screen is sufficient.

A further possibility is that the handle 31 is secured to the frame 27 in such manner that it occupies an invariable position with respect to the screen 11 and is connected with the rod 23 by means of a universal joint whose centre is located in the axis 42. In this case the rotary

motion of the handle may be transferred to the screen by means of a gear wheel and a toothed rack which is rigidly secured to the screen or by means of a simple crank mechanism.

In all these cases the handle may also be secured directly to the slideable portion of the screen so that the movement is transferred from the screen via a gear wheel or a crank to the coupling rod 23. The slider may be provided, for example, on the sides, with straps for taking hold thereof.

What I claim is:

1. X-ray apparatus comprising a screen member, an X-ray tube movable in a plane parallel to said screen, two column members, a tube supporting member comprising a housing adapted to move along one of said columns for moving said tube longitudinally in a plane parallel to said screen and a rotatable spindle supported by said housing adapted to move said tube transversely in a plane parallel to said screen, a flexible telescopic shaft member adapted to vary in length as said X-ray tube is moved longitudinally in a plane parallel to said screen, means to rotate said shaft member corresponding to a transverse movement of said tube, a screen supporting member comprising a housing adapted to move along the other of said columns for moving said screen longitudinally in a plane parallel to the plane of movement of said tube and a transverse member supported by said housing adapted to move said screen transversely in a plane parallel to the plane of movement of said tube, means coupling said shaft member to said transverse member to produce a corresponding movement of said screen when said tube is moved transversely relative to said shaft, and a pivotal member coupling said shaft member to said screen supporting member to permit axial movement of said shaft about said screen supporting member for positioning said tube so that the center of the beam from the tube remains aligned with the center of the screen as said tube is moved longitudinally relative to said screen.
2. X-ray apparatus comprising a screen member, an X-ray tube movable in a plane parallel to said screen, two column members, a tube supporting member comprising a housing adapted to move along one of said columns for moving said tube longitudinally in a plane parallel to said screen and a rotatable spindle member supported by said housing adapted to move said tube transversely in a plane parallel to said screen, a flexible telescopic shaft member adapted to vary in length as said X-ray tube is moved longitudinally in a plane parallel to said screen, means to rotate said shaft member, means to couple said shaft member to said spindle member to move said tube transversely to said shaft member when said shaft is rotated, a screen supporting member comprising a housing adapted to move along the other of said columns for moving said screen longitudinally in a plane parallel to the plane of movement of said tube and a transverse member supported by said housing adapted to move said screen transversely in a plane parallel to the plane of movement of said tube, means coupling said shaft member to said transverse member to produce a corresponding movement of said screen when said tube is moved transversely relative to said shaft so that the beam from the tube remains aligned with the center of said screen, and a pivotal member coupling said shaft to said screen supporting mem-

ber to permit axial movement of said shaft about said screen supporting member for positioning said tube so that the center of the beam from the tube remains aligned with the center of the screen as said tube is moved longitudinally relative to said screen.
